UNITED STATES PATENT OFFICE.

EUGÈNE HENRI TARTRAIS, OF MONTMORENCY, FRANCE.

MEANS FOR LUBRICATING VALVES.

1,071,112.

Specification of Letters Patent. Patented Aug. 26, 1913.

Application filed June 15, 1912. Serial No. 703,853.

To all whom it may concern:

Be it known that I, EUGÈNE HENRI TARTRAIS, citizen of the French Republic, and residing at 32 Rue des Chesneaux, Montmorency, Seine-et-Oise, France, have invented certain new and useful Improvements in or Relating to Means for Lubricating Valves, of which the following is a specification, reference being had therein to the accompanying drawing.

This invention relates to improved means for lubricating the valves of internal combustion engines and refers particularly to rotary valves.

15 The invention may be broadly described as consisting in providing means whereby the lubricant is thrown from the interior of the crank case through passages or conduits against the said valves, the said throwing being effected either or both by centrifugal action and by a pump.

In the accompanying drawings, Figures 1, 2 and 3 show one method of carrying out my invention, Fig. 1 being a vertical cross section on the line A—B of Fig. 2 which illustrates a four-cylinder engine the valve of which is shown in elevation, the drawings being a section on the line C—D of Fig. 1. Fig. 3 is a horizontal section through the axis of the valve and on the line G—H of Fig. 1. Fig. 4 is a modification, partly in section, of the device, showing a passage formed in the crank, the arm or webs of which are provided with extensions. Fig. 5 shows the web of the crank to be sloped so as to throw the oil onto the connecting rod bearings. Fig. 6 shows cups fixed to the web of the crank, and furnished with oil bearing extensions.

40 Referring to Figs. 1, 2 and 3, the webs 1 of the crank are furnished with disks 4 running in the oil 2 in the crank case 3 in such a manner that their rotary movement forcibly throws the oil in their plane of rotation.

45 A portion of this oil is thrown along the conduits 5 arranged beside the cylinders 8 and falls against the wall of the valve 6. It will be seen, particularly in Fig. 2, that

the outlets 7 from the conduits 5 are placed out of the paths of the ports 9¹, 9², 9³, 9⁴ 50 and 10¹, 10², 10³, 10⁴, so as to avoid leakage. The oil on the valve is carried around by it and owing to the slight free play between the valve and its casing travels thoroughly over the bearing surface of the valve being 55 spread out so as to thoroughly lubricate it. Grooves such as 11, 11', 12, 13 and 13' are preferably provided in the valve casing and are of interrupted helical form for the purpose of preventing direct communication between the inlet to one cylinder and the exhaust of another, during the rotation of the valve.

In the modification shown in Fig. 4 a passage is formed in the crank the arms or 65 webs 14 of which have extensions 15 and the oil is forced through the passages and thrown out of the extensions, or the oil may be collected by means of cups on the crank.

In Fig. 5 the web of the crank is sloped at 70 16, 16', so as to throw the oil onto the connecting rod bearings, the oil having a tendency to travel to the edge 17 of the said slopes.

In Fig. 6 the arrangement shown comprises cups 18 fixed to the web of the crank 75 and furnished with extensions 19 through which the oil is thrown on to the bearings.

Having now particularly described and ascertained the nature of my said invention 80 and in what manner the same is to be performed, I declare that what I claim is:—

1. Means for lubricating valves, comprising a casing, the lower part of which constitutes an oil receptacle, a crank in said casing having a web, a disk on said web adjusted to contact with the oil in said receptacle, conduits in the plane of rotation of said disks upon which the oil is thrown from said disks and conducted to the wall 90 of the valve, the movement of the valve causing the oil to be spread over its bearing surface.

2. A device for lubricating the slide valves of internal combustion engines, comprising a casing forming an oil receptacle, 95

a crank shaft in said casing, means upon the crank shaft for projecting the oil, conduits disposed in the planes of projection, and tangential to the exterior trajectory, of the crank shaft, cylinders adjacent to the said conduits, a slide valve at the ends of said conduits receiving the oil projected by the crank shaft, the said conduits opening into

the said valve, outside or the field of displacement of the distribution orifices 10

In testimony whereof I affix my signature in the presence of two witnesses.

EUGÈNE HENRI TARTRAIS.
